(57) **CLAIM**

The ornamental design for an instrument string winder, as shown and described.

DESCRIPTION

FIG. 1 is a perspective view of an instrument string winder; FIG. 2 is a top plan view of the instrument string winder shown in FIG. 1;

FIG. 3 is a bottom plan of the instrument string winder shown in FIG. 1;

FIG. 4 is a front elevation view of the instrument string winder shown in FIG. 1; and

FIG. 5 is a rear elevation view of the instrument string winder shown in FIG. 1;

FIG. 6 is a right side elevation view of the instrument string winder shown in FIG. 1; and,

FIG. 7 is a left side elevation view of the instrument string winder shown in FIG. 1.

The broken lines are included for the purpose of illustrating portions of an instrument string winder and form no part of the claimed design.

1 Claim, 6 Drawing Sheets
